UNITED STATES PATENT OFFICE.

JOHN H. McCLOY, OF PITTSBURGH, PENNSYLVANIA.

COUPLING.

Application filed December 6, 1922. Serial No. 605,317.

To all whom it may concern:

Be it known that I, JOHN H. McCLOY, a citizen of the United States, residing at Pittsburgh, in the county of Allegheny and

5 State of Pennsylvania, have invented certain new and useful Improvements in Couplings, of which the following is a specification.

This invention relates to couplings particularly designed for connecting the adjacent or conjoining ends of the leg members, girts, and braces constituting the frame-work of a deep drill hole steel derrick, such as that of an oil well, for supporting the tackle for boring or hoisting or lowering, and while primarily adapted for use in conjunction with the framework of a steel derrick, it will be obvious that my improved coupling may be employed for any purposes wherein it is found to be applicable.

Important objects of the invention are to provide a substantial coupling unit for securing the adjacent ends of steel derrick 25 frame-work members, which will facilitate the erection and dismantling of such derrick structures, and which includes novel means for maintaining the coupling in condition for convenient detachment.

30 Further objects of this invention are to provide a device of the character described, in a manner as hereinafter set forth, which is simple in its construction and arrangement, strong, durable and efficient in its use, positive in its action, and comparatively inexpensive to manufacture.

To the accomplishment of these and such other objects as may hereinafter appear, the invention consists of the novel construction, 40 combination and arrangement of parts hereinafter specifically described, and illustrated in the accompanying drawing wherein is shown an embodiment of the invention, but it is to be understood that changes, variations, and modifications may be resorted to which come within the scope of the claims hereunto appended.

In the drawing forming a portion of this specification and wherein like numerals of 45 reference designate corresponding parts throughout the several views:—

Figure 1 is a perspective view of my improved coupling, illustrating the attachment of conjoining derrick structure members 55 therewith.

Figure 2 is a longitudinal sectional view of the coupling on line II—II, Figure 3.

Figure 3 is a top plan view of the coupling.

Figure 4 is a perspective view of a modified form of coupling. 60

Figure 5 is a vertical sectional view on line V—V, Figure 4.

Figure 6 is a vertical sectional view of another modification of the coupling. 65

Referring in detail to the drawing 1 denotes the body portion of the preferred form of coupling which consists of an integral steel casting. The body portion 1 is cylindrical in contour and is formed with an upper bore 2 and a lower bore 3. The bores 2 and 3 are separated from each other by the centrally disposed seat member 4 which extends around the periphery of the bore intermediate of bores 2 and 3. 70

The marginal edges of the upper and lower faces of the seat member 4, adjoining the peripheries of respective bores 2 and 3, are formed to provide recessed circular finished seats 5 and 6, respectively. 80 The seats 5 and 6 are adapted for the reception of the adjacent ends of the respective leg members 7 and 8, which latter constitute a portion of the framework of the derrick structure and are made from tubing or pipe permitting of their engagement in the recessed seats 5 and 6. 85

The faces of the upper and lower bores 2 and 3 are each provided with a plurality of vertically extending ribs 9 having finished faces adapted to frictionally engage the outer face of the leg members 7, 8, when the latter are mounted in position in respective bores 2 and 3 and seats 5 and 6. Each of the ribs 9 increases in width from its inner to its outer end. 90

It will here be noted that the construction of the body portion 1 providing the machined rib faces and seats 5 and 6, will establish an accurate, substantial, and rigid 95 union between conjoining leg members 7 and 8. The provision of the ribs 9 will not only provide for the economic manufacture of the coupling but will also facilitate the assembly or detachment of the associated members 7 and 8 by reducing their frictional engagement, in respective bores 2 and 3, to a minimum. Further the periphery of the bores 2 and 3 between adjacent vertical ribs 9 provide clearances 10 which are utilized 100

for storing a cheap heavy lubricant to prevent corrosion of the connections and to further facilitate the erection or dismantling of the derrick structure. The varying width 5 of the ribs 9 will serve to confine the lubricant in the clearances 10.

Formed integral with the periphery of the body portion 1 is a pair of longitudinally extending and laterally disposed flanges 10 11, 12, one of said flanges being positioned at right angles relatively to the other. Each of the flanges 11, 12, is provided with three aligned apertures 13, 14, and 15, respectively. The center apertures 14, of the 15 flanges 11, 12, are utilized for securing the horizontal girts 16 to respective flanges 11, 12, and the end apertures 13 and 15 are utilized for securing the diagonally disposed brace members 17 to respective flanges 20 11 and 12. The flange apertures 13, 14 and 15 are elongated for the reception of bolts 18, commonly known to the trade as "track bolts" having shoulders conforming to the contour of the elongated flange apertures 25 13, 14 and 15. Each of the bolts 18 is provided with a securing nut 19 of the usual construction and the adjustment or removal of the latter is facilitated as the engagement of the bolts 18 in elongated flange 30 apertures 13, 14 and 15 is fixed to prevent its rotation. Such construction is essential as the rig builder is usually employed in hazardous positions on derrick construction, supporting himself with the aid of one hand 35 while adjusting the nut 19 upon the bolts 18 with the other.

The modification illustrated in Figure 4 of the drawing shows a coupling comprising a body portion 20 including a complementary section 21, and constructed from steel plate instead of a casting as in the 40 preferred form. The body portion 20 is formed to provide lateral flanges 22, one of which is disposed at right angles relatively 45 to the other. The complementary section 21 is formed with a pair of narrow longitudinal flanges 23, each of which is secured to its respective body portion flange 22 by means of the rivets 24. The body portion 20 and its complementary section 21 50 form a bore 25 having a centrally disposed annular groove 26 preferably pressed outwardly on the periphery of the bore 25. A seat member 27 is mounted in the annular 55 groove 26 and secured therein by the assembly of the section 21 with the body portion 20, as above described.

The seat member 27 is formed to provide an annular seat 28 on the upper face thereof 60 and an annular seat 29 on its lower face. The seats 28 and 29 are provided for the reception of adjacent leg members as described relatively to the preferred form.

The modification shown in Figure 6 provides a coupling identical in construction

as that described relative to the modification shown in Figure 5 with the exception that the seat member 30 is riveted, as indicated at 31, to the body portion instead of being secured therein by means of annular 70 grooves 26.

It will be noted that the two modifications of the coupling provide a structure functioning identically to that disclosed in my preferred form with the exception that 75 the bores thereof are not ribbed or machined and in consequence would not provide as accurate a union as when using the preferred form of coupling.

What I claim is:—

1. A coupling comprising a body portion formed with a bore, means arranged within the body portion and in connection therewith providing a pair of opposingly disposed grooves constituting a pair of seats 85 intermediate the ends of said bore, and angularly disposed flanges projecting from the body portion, and vertically extending ribs integral with the inner face of the body portion.

2. A coupling comprising a body portion formed with a bore, means arranged within the body portion and in connection therewith providing a pair of oppositely disposed grooves constituting a pair of seats 95 intermediate the ends of said bore, and angularly disposed flanges projecting from the body portion, said means formed with an opening and said flanges provided with apertures, and vertically extending ribs 100 integral with the inner face of the body portion.

3. A coupling comprising a hollow body portion having arranged therein a pair of oppositely extending seats, flanges projecting from the body portion, and vertically extending ribs integral with the inner face of the body portion.

4. A coupling comprising a hollow body portion, having arranged therein a pair of 110 oppositely extending seats, and flanges projecting from the body portion, each pair of flanges provided with a plurality of openings, and vertically extending ribs integral with the inner face of the body portion.

5. A coupling comprising a hollow body portion having arranged therein a plurality of seats, and spaced oppositely extending flanges projecting laterally from said body portion, and vertically extending ribs 120 integral with the inner face of the body portion.

6. A coupling comprising a hollow body portion having arranged therein a plurality of seats, and spaced oppositely extending 125 flanges projecting laterally from said body portion, each of said flanges provided with a plurality of openings, and vertically extending ribs integral with the inner face of the body portion.

7. A coupling member comprising a hollow body having arranged therein an integral apertured seat member providing in connection with the body portion a pair of oppositely extending seats, flanges integral with and projecting at an angle from the body portion, and a plurality of ribs projecting from each of said seats. 45
8. A coupling member comprising a hollow body having arranged therein an integral apertured seat member providing in connection with the body portion a pair of oppositely extending seats, flanges integral with and projecting at an angle from the body portion, each provided with a plurality of apertures, and a plurality of ribs projecting from each of said seats. 50
9. A coupling member comprising a hollow body having arranged therein an integral apertured seat member providing in connection with the body portion a pair of oppositely extending seats, flanges integral with and projecting at an angle from the body portion, a plurality of ribs projecting from each of said seats, said flanges disposed at right angles with respect to each other and of a length equal to the length of the body portion. 55
10. A coupling comprising a hollow body portion having arranged therein a pair of oppositely extending seats, flanges projecting from the body portion, and vertically extending ribs integral with the inner face of the body portion, said flanges disposed at an angle with respect to each other and of a length equal to the length of the body portion. 65
11. A coupling comprising a hollow body portion having arranged therein a plurality of seats, and spaced oppositely extending flanges projecting laterally from said body portion. 70

portion, and vertically extending ribs integral with the inner face of the body portion, said flanges disposed at an angle with respect to each other and of a length equal to the length of the body portion. 45

12. A coupling comprising a body portion formed with a bore, means arranged within the body portion and in connection therewith providing a pair of oppositely disposed grooves constituting a pair of seats intermediate the ends of said bore, and angularly disposed flanges projecting from the body portion, and vertically extending ribs integral with the inner face of the body portion, each of said ribs gradually increasing in width from its inner to its outer edge. 50

13. A coupling comprising a hollow body portion having arranged therein a pair of oppositely extending seats, flanges projecting from the body portion, vertically extending ribs integral with the inner face of the body portion, each of said ribs gradually increasing in width from its inner to its outer edge. 60

14. A coupling comprising a hollow body portion having arranged therein a plurality of seats, and spaced oppositely extending flanges projecting laterally from said body portion, vertically extending ribs integral with the inner face of the body portion, each of said ribs gradually increasing in width from its inner to its outer edge. 70

15. A coupling comprising a hollow body portion having lengthwise extending ribs on its inner face, means within the body portion to provide a pair of oppositely extending seats, and flanges projecting from the body portion and extending lengthwise thereof. 75

In testimony whereof I affix my signature.

JOHN H. McCLOY.
